UNITED STATES PATENT OFFICE.

ABRAHAM S. ADLER, OF BALTIMORE, MARYLAND.

SHOE-MAKER'S MEASURE.

SPECIFICATION forming part of Letters Patent No. 337,039, dated March 2, 1886.

Application filed October 6, 1885. Serial No. 179,105. (No model.)

To all whom it may concern:

Be it known that I, ABRAHAM S. ADLER, a citizen of the United States, residing at Baltimore, in the State of Maryland, have invented 5 a new and useful Shoe-Maker's Measure, of which the following is a full, clear, and exact description, reference being had to the accompanying drawings, forming part of this specification, in which—

10 Figure 1 represents a perspective view of a shoe-maker's measure closed and ready for expansion. Fig. 2 represents the measure expanded and a skeleton insole placed in position. Fig. 3 represents a detached view of the 15 skeleton insole. Fig. 4 represents a detail of one of the sliding blocks. Fig. 5 is a detail of a heel stop or plate used in connection with my improved measure.

My invention relates to an improved apparatus for taking measurements of and fitting the human foot, for use in making boots and shoes; and my invention consists, essentially, in a series of sliding blocks, which when closed are of a configuration corresponding to the 25 form of the human foot.

It also consists in a skeleton insole of peculiar construction, and provided with a series of points upon its under surface for engaging the base-plate.

30 It further consists in the sliding blocks having each a transverse plate secured to its under surface, and a guide or groove for the passage of a similar plate upon an oppositely-sliding block, and also in the arrangement of 35 suitable pins upon the plates, whereby when any one or more of the blocks are adjusted laterally the pins engage the base-plate and indicate the exact measurement, all of which I shall hereinafter fully describe, and point out 40 in the claims.

To enable others skilled in the art to make and use my invention, I will now describe its construction and the manner in which I have carried it out.

45 In the said drawings, A represents the base of the apparatus, which may be made of any suitable material and size.

B B' B" B'" represent a series of sliding blocks, which are provided each with a plate, 50 a, extending transversely from each side, and perforated at b for the insertion of a suitable

pin, the purpose of which will be hereinafter fully developed.

In addition to the plate a, each of the sliding blocks has a groove or guide, a', for the 55 reception and guidance of the plate upon the adjoining or oppositely-sliding block.

On blocks B' B" B'" are secured the straps containing a scale for taking the measure around the several parts of the foot, and the 60 base-plate is provided with a removable heel-plate, H, against which the heel of the person rests during the taking of the measure. This heel-plate, as shown in Fig. 5, has a tongue, e, which engages slots in the base-plate, whereby the heel-plate may be readily removed when not in use, and also has measuring-straps secured thereon for taking the exact heel and ankle measurement.

D represents a skeleton insole, and this may 70 be made of any appropriate material and of such size as to correspond exactly with the insole of the shoe when the parts are adjusted. This skeleton insole fits between the blocks when the latter are extended, as shown in Fig. 75 2, and corresponds exactly with the outline of the upper portions of the sliding blocks, so that when said insole is placed in position the outline of the inner sole is complete. The skeleton insole D is grooved transversely at g 80 for the free passage of the plates a, and also has a series of points or pins, h, which engage the base-plate and hold the skeleton sole in position. As before stated, the plates a are provided with a perforation, b, and have 85 mounted upon their upper surface a pin, l, which, when any one of the sliding blocks are adjusted laterally to obtain the desired measurement, are pressed downward, passing through the perforations and holding the 90 block in its position until released by the operator.

The operation of my apparatus is as follows: If a foot requiring a specified number shoe is to be measured, the blocks are adjusted, in 95 connection with a correspondingly-numbered skeleton sole and a suitable diagram; but when the foot itself is placed in position on the blocks the appropriate insole is introduced, and the straps D are adjusted in the usual way to the 100 different parts of the foot. If a broader sole and less upper is desired, the blocks are ad-

justed outwardly. When the foot has been thus fitted to the entire comfort of the person, the pins *l* are passed down through the holes *b* in the guide-plates to hold the blocks steadily in position while the foot is being measured, and these pins may be used in connection with a diagram of paper or other material, as shown in my Patent No. 322,238.

Having thus described my invention, what I claim as new, and desire to secure by Letters Patent, is—

1. In a shoe-maker's measuring device, a series of independent sliding blocks having transverse plates and suitable guides secured thereon, whereby the said blocks are adjusted toward or from each other, substantially as herein described.
2. In a shoe-maker's measuring device, a series of sliding blocks, in combination with the plates, the guides, and the pins mounted upon the plates and adapted to pass through perforations in the same, substantially as herein described.
3. In a shoe-maker's measuring device, a skeleton insole constructed to correspond to the configuration of the foot, substantially as herein described.

4. In a shoe-maker's measuring device, the combination, with a series of adjustable blocks, of a skeleton insole placed between and corresponding to the form of said blocks, substantially as herein described. 30

5. In a shoe-maker's measuring device, the combination of laterally-adjustable blocks of a skeleton insole provided with points of attachment to a base-board, substantially as herein described. 35

6. The combination, with a slotted base-board, of a removable heel-plate provided with measuring-straps and locking-tongue, 40 substantially as herein described.

7. An improved shoe-maker's measuring device comprising a base-plate, a series of adjustable blocks having measuring-straps, a removable heel-plate having measuring-straps, 45 and devices for holding the blocks in a fixed position after adjustment, substantially as herein described.

ABRAHAM S. ADLER.
